CURTAIN STRETCHER

Allen K. Mitchell, Jr., Munhall, Pa.

Application December 10, 1932
Serial No. 646,637

6 Claims. (Cl. 45—24)

My invention relates to curtain stretchers, and more particularly to those which are supported in the manner of an easel.

One object of my invention is to provide 5 stretcher bars and connections of such form and arrangement that the clamping of the bars in assembled relation will automatically bring the bars into true rectangular formation.

Another object of my invention is to provide an 10 improved form of clamping structure for the corners of the stretcher frame.

Still another object of my invention is to provide an improved form of leg support.

One form of my invention is shown in the 15 accompanying drawing wherein Figure 1 is a face view of a curtain stretcher; Fig. 2 is an end elevational view thereof; Fig. 3 is an enlarged view taken on the line III—III of Fig. 2; Fig. 4 is a face or plan view of one of the clamping devices; 20 Fig. 5 is an enlarged view taken on the line V—V of Fig. 2; Fig. 6 is an enlarged face view of a portion of the structure of Fig. 1, and Fig. 7 is an edge view thereof.

The stretcher is provided with the usual edge 25 bars 9 and 10, and end bars 11 and 12, the bar 12 having a detachable section 12a which may be folded backwardly to inoperative position in a manner to be hereinafter described. The bars are all provided with pin-like members 13 upon 30 which the edges of the curtains may be hooked in the usual manner.

Each of the bars 9, 10, 11 and 12 has secured thereto at one end a clamping bracket 15 which is in the form of a metal plate or strip secured to 35 the bar by screws, as shown more clearly in Figs. 3 and 4. The outer end of each plate 15 is offset from its body portion, as shown more clearly in Fig. 3, and such offset portion carries a rivet or pivot pin 16, and an extended housing-like portion 17. A cam lever 18 is pivotally connected to 40 the pivot pin 16, and has a camming disc 19 which is movable against a shoulder of a clamping block 20, the block 20 having a slotted extension through which the pin 16 extends.

45 It will be understood that when the clamping lever 18 is swung to bring the cam disc 19 into engagement with the shoulder of the block 20, the block will be forced inwardly and move the adjacent stretcher bar into position against the end 50 of the bar which carries the clamp. This clamping action, of course, results in the bars of each corner being brought into right angle relation to one another, so that when assembled, the frame will be truly rectangular. The bracket members 55 15 may suitably be of pressed metal, and by reason of their stepped or offset form, will yield slightly under thrust imparted by the clamping force.

The lower end of the stretcher bar 12 rests 60 upon the upper edge of the bar 9, while the upper end of the bar 11 has direct engagement with the

lower edge of the upper bar 10. In making horizontal adjustments to suit curtains of various lengths, the clamps at the corners A and B will be loosened, whereupon the end bar 11 and its associated longitudinal bar 9 can be shifted longitudinally of the bar 10 to the desired position. The clamps at A and B are then tightened. 65

In order to effect adjustment to curtains of various widths, the clamps at the corners C and D are loosened, whereupon the bar 9 and its associated bar 12 can be slid vertically the desired distance, and the clamps at C and D then tightened. 70

A leg of any suitable form is provided at the rear side of the bar 11, the upper end of such leg being pivoted to the bar at 22. At the other end of the stretcher, a leg of different form must be provided since the lower end of the bar 12 does not extend to the floor. For this reason, I provide a two-part leg, the front portion of which is 75 indicated by the numeral 23 and the rear portion by the numeral 24. The leg member 23 is supported against side sway by a clip 25 which is secured to the rear side of the bar 12. A toggle connection 26 is employed to hold the leg members 23 and 24 in expanded relation, and the leg 24 is pivotally connected by a bracket 27 to the leg member 23. 80

The upper end of the leg member 23 is connected to the bar 10 by a bolt 28, as shown more 85 clearly in Fig. 3. Since with the adjustments at the corners of the frame as heretofore described, the bars 10 and 11 are never adjusted vertically, but only the bars 9 and 12, the vertical positions of the legs which are connected to the bars 10 and 11 are not disturbed relative to the floor 90 upon which the stretcher is placed. It will, of course, be understood that a single-bar leg similar to the member 24 can be employed for the bar 11, but that because the bar 12 does not extend clear 95 to the floor, an additional leg member 23 must be provided at that end of the frame. 100

For ordinary or narrow width curtains, the bar section 12a may be dispensed with, and the bar 12 raised far enough so that it will be engaged by the 105 clamp at C, to thereby connect it directly to the bar 10.

The bar section 12a is so connected to the section 12 that it may be swung back out of the way, which is, of course, a desirable feature where the 110 stretcher is located in a room that has a low ceiling. This connection is effected by means of a splice plate 30 that is disposed in slots formed within the adjacent ends of the bar sets 12 and 12a. The splice plate is held in position in the 115 section 12 by means of pins or rivets 31, and the section 12a is pivotally connected to the plate by a pin 32. The front portions of the sections 12 and 12a have abutting surfaces at 33, but their rear surfaces have clearance at 34, so that the 120

section 12a can be swung back and folded down when the bar 10 is disconnected from said section, as by moving the bar section 12 up.

In order to prevent lateral tilting of the bar 12 relative to the bar 12a, when the extension 12a is being used, I provide a stop member 40 mounted on the inner side of the leg member 23. The stop member 40 is pivotally mounted on a pin which has a thumb nut 41, by means of which the stop member may be held in operative position. The stop member 40 will, of course, be turned forwardly to overlie the inner side of the bar 12.

I claim as my invention:—

1. A curtain stretcher comprising a rectangular frame composed of end bars and edge bars disposed in a common plane, means for detachably clamping each bar at one end thereof to the adjacent bar at corners of the frame, for adjustment longitudinally of its adjacent bar, means for supporting the frame in substantially an upright position comprising a leg connected to one end bar in inclined relation thereto, a supporting bar disposed at the rear side of the frame adjacent to the other end bar and connected to the edge bar at the top of the frame, said supporting bar extending parallel to the said other end bar past the edge bar at the lower edge of the frame, and an inclined leg connected to said supporting bar, the lower edge bar and said other end bar being adjustable transversely of the upper edge bar in directions longitudinally of said supporting bar.

2. A curtain stretcher comprising a rectangular frame composed of end bars and edge bars disposed in a common plane, means for detachably clamping each bar at one end thereof to the adjacent bar at corners of the frame, for adjustment longitudinally of its adjacent bar, means for supporting the frame in substantially an upright position comprising a leg connected to one end bar in inclined relation thereto, a supporting bar disposed at the rear side of the frame adjacent to the other end bar and connected to the edge bar at the top of the frame, said supporting bar extending parallel to the said other end bar past the edge bar at the lower edge of the frame, an inclined leg connected to said supporting bar, the lower edge bar and said other end bar being adjustable transversely of the upper edge bar in directions longitudinally of said supporting bar, and means secured to the rear side of one of the last-named bars adjacent to the corner thereof, and slidably engaging said supporting bar, for preventing lateral movement thereof relative to the frame.

3. A curtain stretcher comprising a rectangular frame composed of end bars and edge bars disposed in a common plane, means for detachably clamping each bar at one end thereof to the adjacent bar at corners of the frame, for adjustment longitudinally of its adjacent bar, means for supporting the frame in substantially an upright position comprising a leg connected to one end bar in inclined relation thereto, a supporting bar disposed at the rear side of the frame adjacent to the other end bar and connected to the edge bar at the top of the frame, said supporting bar extending parallel to the said other end bar past the edge bar at the lower edge of the frame, an inclined leg connected to said supporting bar, the lower edge bar and said other end bar being adjustable transversely of the upper edge bar in directions longitudinally of said supporting bar, and an extension bar pivotally connected to the upper end of said other

end bar and normally disposed rearwardly thereof, said extension bar being movable into the plane of said other end bar to cooperate therewith at a predetermined position of adjustment thereof.

4. A curtain stretcher comprising a rectangular frame composed of end bars and edge bars disposed in a common plane, means for detachably clamping each bar at one end thereof to the adjacent bar at corners of the frame, for adjustment longitudinally of its adjacent bar, means for supporting the frame in substantially an upright position comprising a leg connected to one end bar in inclined relation thereto, a supporting bar disposed at the rear side of the frame adjacent to the other end bar and connected to the edge bar at the top of the frame, said supporting bar extending parallel to the said other end bar past the edge bar at the lower edge of the frame, an inclined leg connected to said supporting bar, the lower edge bar and said other end bar being adjustable transversely of the upper edge bar in directions longitudinally of said supporting bar, and an extension bar pivotally connected to the upper end of said other end bar and normally disposed rearwardly thereof, said extension bar being movable into the plane of said other end bar to cooperate therewith at a predetermined position of adjustment thereof, the pivotal connection being disposed entirely within the surface planes of said extension bar and said other end bar.

5. A curtain stretcher comprising a rectangular frame composed of end bars and edge bars disposed in a common plane, means for detachably clamping each bar at one end thereof to the adjacent bar at corners of the frame, for adjustment longitudinally of its adjacent bar, means for supporting the frame in substantially an upright position, comprising a leg connected to one end bar in inclined relation thereto, a supporting bar disposed at the rear side of the other end bar and connected to the edge bar at the top of the frame, said supporting bar extending parallel to the said other end bar past the edge bar at the lower edge of the frame, and an inclined leg connected to said supporting bar, the lower edge bar and said other end bar being adjustable transversely of the upper edge bar in directions longitudinally of said supporting bar.

6. A curtain stretcher comprising a rectangular frame composed of end bars and edge bars disposed in a common plane, means for detachably clamping each bar at one end thereof to the adjacent bar at corners of the frame, for adjustment longitudinally of its adjacent bar, means for supporting the frame in substantially an upright position, comprising a leg connected to one end bar in inclined relation thereto, a supporting bar disposed at the rear side of the other end bar and connected to the edge bar at the top of the frame, said supporting bar extending parallel to the said other end bar past the edge bar at the lower edge of the frame, an inclined leg connected to said supporting bar, the lower edge bar and said other end bar being adjustable transversely of the upper edge bar in directions longitudinally of said supporting bar, and a U-shaped clip secured to the rear side of said other end bar adjacent to its lower end, said clip engaging the inner and outer edges of said supporting bar, for preventing lateral movement thereof relative to the frame.
